UNITED STATES PATENT OFFICE

171,901

HAIR CURLING ROD

Louis L. Lerner, Chicago, Ill.

Application April 28, 1953, Serial No. 24,728

Term of patent 14 years

(Cl. D86—10)

To all whom it may concern:

Be it known that I, Louis L. Lerner, a citizen of the United States, residing at Chicago, in the county of Cook and State of Illinois, have invented a new, original, and ornamental Design for a Hair Curling Rod, of which the following is a specification, reference being had to the accompanying drawing, forming a part hereof, wherein:

Fig. 1 is a view in front elevation of a hair curling rod showing my new design;

Fig. 2 is a view in side elevation;

Fig. 3 is an end view;

Fig. 4 is a view along line 4—4 of Fig. 1;
Fig. 5 is a view along line 5—5 of Fig. 1.

I claim:

The ornamental design for a hair curling rod, as shown.
